UNITED STATES PATENT OFFICE.

ALFRED E. SMITH, OF BRONXVILLE, NEW YORK.

HOLDER FOR PENS, PENCILS, &c.

1,174,770.

Specification of Letters Patent.

Patented Mar. 7, 1916.

Application filed February 3, 1914. Serial No. 816,324.

To all whom it may concern:

Be it known that I, ALFRED E. SMITH, a citizen of the United States of America, and a resident of Bronxville, in the county of 5 Westchester and State of New York, have invented a certain new and useful Holder for Pens, Pencils, &c., of which the following is a specification, the same being a full, clear, and exact description of the invention, such as will enable others skilled in the art to which it appertains to make and use the same.

My invention relates to receptacles adapted to receive and sustain various articles, 15 and in particular to a holder or container designed to be used especially for a certain class of instruments, such, for example, as those terminating in a point and split at the nib and used for writing by means of a fluid ink, and also as those employing graphite for use in marking, drawing, or writing, and having a tapering and pointed end portion. Instruments of this character are ordinarily laid, either flatwise on a desk, etc., 25 where they are apt to be in the way, or else, on an inkstand or in a rack which is usually placed at an inconvenient location and at some distance away from the operator, where they are not handy for quick use.

30 The object of this invention is to provide a pencil and pen holder that will sustain the same either in a vertical relation, or at a suitable angle to the base, so as to be out of the way and still close to the hand of the user 35 so as to be at all times readily accessible.

To attain the desired end, the invention consists in the construction and arrangement of parts and the combination of the same in a serviceable and efficient relation.

40 In order to enable the invention to be fully understood, I shall proceed to explain the same by reference to the drawings, illustrative of one embodiment of the invention, which accompany and form a part of this 45 specification, and in which—

Figure 1 is a side elevation of a device constructed according to my invention. Fig. 2 is a plan view of my holder without the base. Fig. 3 is a view in detail of my 50 headed wire, and Fig. 4 is a side elevation of another embodiment of the invention.

Like letters of reference indicate like parts in all the views.

In carrying out my invention I ordinarily assemble together a mass of wires either so as to stand in a vertical position or else preferably at an angle to the face of the frame or base serving to sustain the mounting or bed in which my wires are placed. These wires, as A, preferably have enlarged head portions, as a, positioned at the outer or free ends of the same, the said heads being preferably so made that the central part thereof shall be higher than the remainder of the heads in order to provide entering interstices between any two adjacent wires. 55 From the raised central portion, the heads preferably taper down toward the circumference or outer edge of the same, although the conformation of the heads may be varied according to the requirements of any particular use thereof. The lower parts of the heads are preferably turned inwardly and so made as to provide faces in relatively flattened form so as to constitute yieldable, 60 laterally disposed gripping points. The opposite extremities of the wires are preferably inserted or molded in a suitable mounting, as for example, a bed of flexible, yielding or elastic material, as B, preferably made of rubber in order that the resilient property of the same shall serve to allow the wires to yield and separate readily when an instrument is inserted therebetween, and also to afford a better or 65 clinging grip on the inserted article. The said elastic mounting also serves to bring the yieldable wires back to their normal positions again when the pencil etc. is removed from the holder.

It will be obvious to one skilled in the art that the described article, comprising a mass of headed wires and an elastic base therefor may be made in a great variety of forms and sizes, in all of which the readily 70 separable and clinging grip properties of my invention will be present, and also that the said device may be supported on a base in any convenient or preferred manner, or, if desired, the holder may be used without the employment of any supporting frame whatsoever. I, however, prefer to provide my pen and pencil holder with a backing or supporting frame of a suitable and approved description as a flat body, or preferably one having a socket or well, such, for 75 80 85 90 95 100 105

example, as the base C, which is ordinarily formed with a recess or socket constituting a rigid curb or rim C' in which the flexible mounting or elastic bed containing the wires is inserted, and if desired, cemented thereto. I also prefer to use in connection with my invention a curb or rim, elastic or otherwise, to surround and inclose the wires, which rim may either be of a low height, such as shown at b, in Fig. 1, or else it may extend upwardly to within a comparatively short distance from the heads of the wires, such as represented in the drawings at b', in Fig. 4.

15. In some cases, in lieu of making the holder or support so as to stand upon a desk, table, etc., I prefer to suspend it in a suitable manner, such as by the use of a base, as D, as illustrated in Fig. 4, which support may be formed with suitable means of attachment, such as an orifice, as d, in order to be conveniently hung up against the wall or the like.

20. In operation, the pen or pencil may be instantly inserted into the mass of wires which will separate and allow the instrument to enter therebetween without any danger of injury to the nib of the pen or the point of the pencil.

25. By the employment of my invention quite a number of pens and pencils may be compactly placed together in the device, if desired, which will hold them so that they will not have to lie on the desk and they will thus be gotten out of the way, and yet be in a convenient position to be quickly grasped by the hand when wanted for use. It will thus be seen that my device comprises a plurality or bunch of parallel wires 30 or strands, as A, assembled closely together, and an elastic bed, as B, of sufficient thickness and firmness to hold the same *per se* in juxtaposition or massed together. The said bed serves to grasp the inner ends of 35 the mass or body of wires with a positive grip and to normally support and to partially obstruct or retard, but not to entirely prevent, movement at the said inner ends. In connection with the before named elements I also use a casing therefor having a 40 rigid curb, wall or rim, as C', extending around the said bed to prevent any lateral movement whatever of the bed and wires at the inner portions thereof and to permit 45 lateral movement of the wires at their free extremities and to limit the extent thereof according to the height of the said inclosing rigid curb or rim, whereby the farther the pen, etc., is inserted into the holder the 50 tighter the grip thereof becomes. Obviously the wires may be placed at any desired distances apart from each other as, for example, where the device is required to be used for pens alone, the wires may be posi-

tioned more nearly together than where it 65 is used for both pens and pencils simultaneously.

The elastic bed or mounting may be made integrally in one piece, or it may comprise a bed composed of a plurality of sections if 70 so desired, each one holding one or more wires. My device is thus not only simple and efficient, but it is also durable as well, as there are no parts in it that are liable to become broken or worn out by use. In cases 75 where an elastic rim of sufficient height and resilience is used, the bed may be of flexible, but not necessarily elastic, material.

I wish it to be understood that I do not desire to be limited to the exact details of 80 construction shown and described, for obvious modifications will occur to a person skilled in the art.

What I claim as my invention is:—

1. In a device of the class described, a 85 plurality of wires assembled together, and an elastic base or bed adapted to grasp the wires with a positive grip and to support and retain the same in the desired positions solely by the elasticity of the bed, whereby 90 a gripping action is established between the said wires and bed sufficient to return the wires to their normal positions after having been separated by an entering instrument, the said wires having enlarged outer or 95 free portions forming heads, the central parts of the heads being higher than the remaining portions to allow a free entrance therebetween of an instrument, and the lower parts of the heads being made in relatively flattened form to afford a grip to produce resistance to the withdrawal of the 100 said instrument.

2. In a device of the class described, a 105 plurality of parallel strands assembled closely together, and an elastic bed of sufficient thickness and firmness to hold the mass in juxtaposition and to grasp the inner ends thereof with a positive grip and to normally support and retain the same in 110 the desired parallel positions and to retard movement at the said inner ends, in combination with a casing having a rigid curb or rim extending around the said bed to prevent any lateral movement whatever of 115 the bed and strands at the inner ends thereof, and to permit lateral movement of the strands at their free extremities but to limit the extent thereof, whereby the farther an instrument is inserted into the 120 device the tighter the grip thereof becomes.

3. In a device of the class described, a 125 plurality of yieldable wires assembled together, and an elastic base or bed adapted to grasp the wires with a positive grip and to support and retain the same in the desired positions solely by the elasticity of the bed and wires, whereby a gripping ac-

tion is established between the said wires and bed sufficient to return the wires to their normal positions after having been separated by an entering instrument, in combination with a casing having a rigid curb or rim extending around and inclosing the said bed, to permit lateral movement of the wires and to limit the extent thereof.

Copies of this patent may be obtained for five cents each, by addressing the "Commissioner of Patents, Washington, D. C."

In testimony of the foregoing specification I do hereby sign the same in the city of New York, county and State of New York, this 24th day of January 1914.

ALFRED E. SMITH.
